UNITED STATES PATENT OFFICE.

MILTON B. HILL, OF BOSTON, MASSACHUSETTS.

DESIGN FOR A CUFF-HOLDER.

SPECIFICATION forming part of Design No. 27,240, dated June 22, 1897.

Application filed March 10, 1897. Serial No. 626,890. Term of patent 7 years.

To all whom it may concern:

Be it known that I, MILTON B. HILL, a citizen of the United States, residing in Boston, in the county of Suffolk and State of Massachusetts, have invented and produced a new and original Design for Cuff-Holders, of which the following is a specification.

My invention relates to a design for a cuff-holder, and the leading feature thereof consists in a longitudinal stem or shank having a head (illustrated extending in opposite directions therefrom) provided with transverse portions at its outer ends, said stem and head having substantially the appearance of the conventional two-edged battle-ax. This form of cuff-holder embodies, among other advantages, those of general beauty and convenient shape for the purpose for which it is intended.

In the drawing accompanying and forming part of this specification, the figure is a perspective view of a cuff-holder, showing the design.

My design is composed of a longitudinal stem or shank A, having a headed portion B at one end in the shape, substantially, of a two-edged battle-ax. The stem is illustrated as having rounded edges 7, which connect with the concave portion 8 on the under side of the head B, although it may be of any desired configuration.

The head B of the device extends oppositely from the stem and has at its outer ends the transverse portions 2 and 3, the edges of which are curved longitudinally, as shown at 4 and 5, respectively, and are also blunt or rounded, as at 6.

What I claim is—

The design for a cuff-holder, substantially as shown and described.

MILTON B. HILL.
